ORCHARD HEATER

William C. Scheu, Upland, Calif., assignor, by direct and mesne assignments, of one-half to Scheu Products Company Limited, of Upland, Calif., a corporation of California, and one-half to California Orchard Heater Company, Los Angeles, Calif., a corporation of California

Application March 14, 1932, Serial No. 598,741

9 Claims. (Cl. 158—91)

This invention relates to liquid fuel heaters adapted for orchard heating and particularly to an orchard heater having an improved form of combustion housing.

- 5 The invention further relates to a combustion housing adapted for use with a liquid fuel heater of conventional construction, providing an improvement in the combustion features of said heater.
- 10 The principal object of this invention is to provide an orchard heater having an improved form of combustion housing adapted to effect a super-heating of the combustible fuel vapors entering said housing, prior to the actual combustion of such vapors, whereby the combustion efficiency 15 of the heater is materially improved.
- 15 A further object of the invention is to provide improved means for combustion of the previously heated vapors.
- 20 A particular object of the present invention, in its preferred embodiment, is to provide an orchard heater of the above described type wherein the heated vapors aforesaid are caused to enter the combustion housing at points adjacent 25 the lower portion thereof and caused to rise in said housing, preferably with a rapidly increasing velocity, to a higher level spaced upwardly from said points of entrance, and wherein combustion air is admitted to said combustion housing at a 30 point below the point of entrance of said heated vapors and also at a point adjacent said higher level, whereby, due to the high velocity of said heated vapors in passing said second-named point of air admission, substantially complete combustion 35 of said vapors is subsequently obtained adjacent this point and in the upper portion of the combustion housing, producing a minimum quantity of unburned carbon in the form of soot in the exit gases.
- 40 A further object of this invention is to provide a liquid fuel orchard heater provided with a combustion housing having improved means whereby the inner walls thereof may be easily cleaned of any adhering substances such as soot.
- 45 Further objects of the invention will be brought out in the following description or will be apparent therefrom.

The orchard heater combustion housing of the present invention is adapted to be placed or used upon a heater base portion of any suitable type provided with a fuel storage receptacle and with air admitting means for effecting vaporization of such fuel. Such vaporization is ordinarily obtained by means of a relatively small vaporizing flame maintained in said heater base portion which heats and vaporizes the fuel, and the vapors so produced pass upwardly into the combustion housing.

An important feature of this invention consists in the provision of a vapor heating means

within the combustion housing, so arranged as to be heated by the combustion within said housing and adapted to receive the fuel vapors formed as above described and heat the same before delivering the same into contact with air for supporting the main combustion operation. The combustion housing comprises a lower portion surrounding the vapor heater and an upper portion or stack extending upwardly above the upper end of the vapor heater. The lower portion of the combustion housing is formed as an outer housing of somewhat larger diameter than the vapor heater, providing an annular space therebetween which serves as a mixing and combustion chamber. The vapor heater has openings leading from the interior thereof into the lower portion of said annular space, and the combustion housing is also provided with means for admitting air to said space. A portion of this air is preferably admitted upwardly through openings in the bottom of the combustion housing, and additional air is preferably admitted through openings in the side of the outer housing adjacent the level of the upper end of the vapor heater, that is, at the upper portion of said space. The vapor heater is preferably disposed substantially centrally within said combustion housing, and serves the further purpose of spreading the vapors outwardly into position to contact air admitted to said annular space and causing the combustion in the lower part of the combustion housing, around and immediately above the vapor heater, to be confined to a region close to the side walls of the combustion housing.

The side walls of the outer housing and the vapor heater preferably converge upwardly toward one another so that the lower portion of the space between said outer housing and said vapor heater is of larger cross-sectional area than the upper portion of said space, whereby the vapors entering the lower portion of said space from the vapor heater are caused, due to the convergence of the space, to accelerate in their passage upwardly through said space. This feature provides a relatively high velocity of the vapors past the upper openings through which air is admitted to said space, obtaining through intermixing of the vapors and air. The upper portion of the combustion housing is formed as a stack extending upwardly from said outer housing, said stack being of much greater cross-sectional area than any portion of the space between the vapor heater and the outer housing and the velocity of gas travel therethrough is correspondingly less, which feature allows the gases to burn within said stack until combustion is substantially complete, materially decreasing the possibility of any unburned portions of fuel vapors being discharged into the atmosphere and chilled. This feature has been found to provide

substantially complete combustion at even high rates of fuel consumption, producing exit gases which are remarkably free of unburned carbon or soot.

- 5 Under some conditions of operation of the heater, namely, when starting the heater, some soot may sometimes be deposited in the space between the vapor heater and the outer housing while the heater is warming up. For the purpose of effecting easy removal of such accumulated soot I provide suitable scraper or brush means rotatably disposed within said outer housing whereby said soot may be scraped from the walls and shaken through the air admitting openings in the bottom of the combustion housing, when desired.
- 10

- 15 The invention may be considered as comprising a combustion housing provided with vapor heating and combustion producing means as 20 above described, adapted to be mounted on any suitable type of combustible vapor generating means, or it may be considered as comprising a complete orchard heater including a base portion adapted to contain liquid fuel and provided 25 with air admitting means for vaporizing such fuel, with said combustion housing mounted thereon.

30 Several embodiments of my invention are illustrated in the accompanying drawings, and referring thereto:

35 Fig. 1 is a vertical section of a preferred embodiment of the invention, showing a complete heater of my invention;

Fig. 2 is a transverse section thereof on line 35 2—2 in Fig. 1, with the cover of the base section removed;

Fig. 3 is a transverse section thereof on line 3—3 in Fig. 1;

40 Fig. 4 is a transverse section thereof on line 4—4 in Fig. 1;

Fig. 5 is a vertical section of a modified form of the combustion housing, provided with an alternative form of vapor heater;

Fig. 6 is a vertical section of another modified 45 form of the invention, showing an alternative form of construction which may be employed;

Fig. 7 is a vertical section of another modified 50 form of combustion housing, embodying an alternative form of stack, and also showing alternative forms of other parts, as hereinafter described.

The form of invention shown in Figs. 1 to 4 may comprise a heater base portion 1 consisting of a fuel receptacle 2 and a cover 3, said fuel receptacle being provided with baffle means 4 secured to the side wall of said receptacle in any suitable manner, as for example, by means of a hook 5 at the outer upper edge of said baffle, said hook being engaged by a loop 6 secured to 60 the said side wall. The baffle may be of any desired type, the form shown being merely typical and comprising two side walls 4a and 4b and an outer wall 4c, said walls 4a and 4b being sloped inwardly of the heater, as shown.

65 The cover of the heater base portion is provided with suitable air admitting means whereby a regulated quantity of air may be admitted to the heater base for the purpose of maintaining a vaporizing flame directed downwardly toward 70 the surface of the liquid fuel within the receptacle, whereby the fuel is heated and combustible vapors evolved therefrom. Any suitable type of air admitting means may be employed and for purposes of description I show means such as 75 indicated at 6' provided on the cover 3 inwardly

of the outer edge thereof. Said air admitting means is shown as comprising an opening 6a in the cover, a cap member 6b hingedly mounted on the cover at 7 and fitting around the edges of the opening 6a, said cap member being 5 mounted for pivotal movement about a hinge axis lying substantially parallel to the plane of said opening, and a plate 8a pivotally mounted as at 8b on said cap member. A plurality of openings 6c are provided in the cap member 6b 10 and an arc shaped opening 8c in plate 8a is adapted to be moved into or out of position of partial or total alignment with one or more of said openings 6c upon rotation of the plate 8a. The plate 8a may be provided with a handle 9 for 15 rotation thereof to regulate the exposed area of the openings 8c.

In addition to the above mentioned vaporizing-flame air-admitting openings the apparatus may be provided, if desired, with a plurality of suitable 20 air inlet holes or openings 3b in the cover 3 for the purpose of admitting relatively small amounts of atmospheric air to the interior of the heater, which air will be mixed with the vapors liberated from the fuel and will be carried upwardly there- 25 with. In this manner, the combustible vapors may be rendered somewhat more easily ignited upon contact with air for the support of combustion, as subsequently described. It will be understood that any of the subsequently de- 30 scribed forms of apparatus may be provided with the above-mentioned openings 3b, if desired.

The combustion housing of the present invention may comprise a vapor heater 11 communicating with the interior of the fuel receptacle 2, a lower portion or outer housing 12 surrounding the vapor heater and an upper portion or stack extending upwardly from said outer housing above the upper end of the vapor heater. The vapor heater shown in the present form of de- 40 vice is formed as an inverted truncated hollow cone provided with a cylindrical depending collar 14 adapted to fit within a circular opening 15 in the cover of the heater base portion. A plurality of openings 16 are provided in the side 45 walls 11a of the vapor heater, adjacent the lower end thereof, communicating with the surrounding space defined by the outer housing 12. The upper end of the vapor heater is closed by a wall 11b, upon which is provided a suitable handle 17. 50 The outer housing 12 is substantially cylindrical in shape, and the combustion housing is provided with a radial bottom wall 18 having a centrally disposed depending flange 19 adapted to receive the upwardly projecting flange or collar 55 3a defining the central opening 15 in the heater base cover 3. Suitable openings 21 are provided in the bottom wall 18 of the housing, through which air for support of combustion may be admitted.

The outer housing 12 is further provided with air inlet means disposed adjacent the upper end thereof, there being shown two rows of slots 22 and 23 for this purpose, the slots of each row overlapping and being overlapped by the slots of 65 the other row. This form of air inlet openings has been found to have a very high combustion efficiency by virtue of the admission of a large quantity of air in a plurality of relatively narrow streams, whereby a very uniform mixture of air 70 and combustible gases is obtained. The flared side walls of the vapor heater, together with the side walls of the outer housing 12 define an annular space A of upwardly decreasing cross-sectional area surrounding said vapor heater, said 75

space being of relatively large cross-sectional area at the lower portion thereof and of relatively small cross-sectional area at the upper portion thereof adjacent the slots 22 and 23, 5 forming a constricted annular throat B. Means are also provided for removing or dislodging deposited soot or carbon from the side walls of the outer housing 12 and from the bottom wall 18, and such means may comprise a 10 plurality of scrapers 24 secured to the side walls 11a of the vapor heater 11 and adapted to scrape the inner side walls of the outer housing 12 and the bottom wall 18 upon rotation of the vapor heater with respect to said walls by means of 15 the handle 17. The scrapers may be of any suitable type, the form shown in Figs. 1, 3 and 4 comprising a strip of strap iron or the like secured to the side wall of the vapor heater as at 25, rotatable therewith, and shaped to conform to the shape of the walls 12 and 18. Any soot or the like scraped from the walls is allowed to fall out through the openings 22 in the bottom walls 18. If desired, the scraping means may comprise a construction such as shown in 20 Fig. 7, comprising a plurality of wire brushes or the like, 24a, disposed on arms 24b secured to the vapor heater 11.

The combustion housing upper portion or stack defining the combustion space C may comprise 30 a substantially cylindrical section 13 provided with a bead 26 adjacent the lower edge thereof adapted to rest upon and be supported by the upper edge of the outer housing 12 and in tight engagement therewith, a reducing collar 27 and an upper portion 13a of smaller diameter than the portion 13. The stack is preferably provided with a portion 28 depending from the bead 26 in such manner as to cover the slots 22 and 23 and prevent access of wind and rain thereto, and the 35 collar 27 is preferably provided with a depending 40 positioning flange 27a. The upper stack portion 13a is also preferably provided with a removable lid or cover 31 at the upper end thereof. The stack may be provided with a flame baffle 29 positioned centrally with respect thereto at the lower end of the upper stack portion 13a, if desired, said baffle being secured in any suitable manner to the collar 27. This baffle obtains a 45 partial confinement of the burning gases within 50 the combustion space C, providing for optimum heating of the vapor heater 11. If desired, the outer housing 12 may be provided with lugs 12a secured to the walls thereof at suitable intervals 55 on the periphery, for the purpose of positioning the stack 13 by engagement with the portion 28, as shown.

If desired, the stack portion 13 may be extended upwardly to a greater height as shown at 13' in Fig. 7, and the upper stack portion 13a of reduced diameter may be dispensed with. This form of stack is preferably provided at its 60 upper end with a reducing collar 27' provided with a hinged cover 31' over the central opening 27'', whereby the entire stack 13' may be opened 65 by removing the collar 27', or, the cover 31' may be laid back, opening only the opening 27''.

The modification of the combustion housing shown in Fig. 5 may comprise a substantially cylindrical vapor heater 38 having its upper end 70 closed by a wall 38a and provided with openings 39 in the side walls thereof after the manner of the openings 16, Fig. 1, and the side walls of the outer housing 41 surrounding said vapor heater are preferably sloped inwardly and upwardly as 75 shown so as to form an annular space A' of up-

wardly decreasing cross-sectional area between said walls and said vapor heater.

The converging side walls of the outer housing 41, together with the vapor heater, form an annular space comparable with that shown in Fig. 5 1, of relatively large cross-sectional area at the lower portion and of relatively small cross-sectional area at the upper portion, forming a throat B'. The outer housing is preferably provided 10 with a plurality of air admitting openings adjacent the level of the throat B', which may be of the type shown in Fig. 1, comprising slots 42 and 43 arranged in over-lapping fashion. The combustion housing is further provided with openings 44 in the bottom wall 41a, after the manner 15 of the openings 21.

The stack may comprise a cylindrical portion 45 provided with a shoulder 46 adapted to be supported on the upper edge of the outer housing 41, and a depending collar 47 flared outwardly from the shoulder 46 adapted to serve as a shield for the openings 42 and 43. The device may be provided with scraper means, if desired, such as is shown at 48 secured to the vapor heater 38 and adapted, by engagement with the bottom wall 25 41a, to support said vapor heater in position within the outer housing 41. The vapor heater may also be provided with a suitable handle 38b whereby said vapor heater may be rotated relative to the outer housing 41 for operation of the 30 scraper means 48.

The combustion housing shown in Fig. 5 may be provided, if desired, with any suitable form of cover for the upper end of the stack, such as 35 shown in Fig. 1 or in Fig. 6.

The form of invention shown in Fig. 6 may comprise a heater base portion 63 having a cover 64 and adapted to contain a liquid fuel to a suitable level such as indicated at "L." The cover 64 is provided with air admitting means 65 for 40 maintaining a vaporizing flame within the base portion, and a central opening 66 defined by a vertically extending flange 67. The vapor heater and combustion housing are adapted to be supported within and without the flange 67, respectively. A cylindrical tubular member 68 extends 45 downwardly from the vapor heater into the base portion 63 through the central opening 66 and is provided with vertical slots or elongated openings 69 for passage of fuel vapors from the base 50 portion 63 into said cylindrical member, said cylindrical member being adapted to serve as a vapor baffle to prevent flashing of the vaporizing flame from beneath the air admitting means 65 upwardly into the combustion housing. The vapor heater may comprise a hollow inverted frusto-conical portion 71 provided with a top wall 71a and vapor outlet openings 72 in the lower portion of the side walls thereof, corresponding 55 to the openings 16, Fig. 1.

The outer housing may in this case comprise a plurality of circular sections 73, 74 and 75 spaced from one another to provide annular air inlet openings 76 and 77 therebetween, as shown. The lower section 73 is preferably provided with a 60 depending collar 73a adapted to fit over the flange 67 on the cover 64 and is further provided a bottom wall 78 having a plurality of air inlet openings 78a, allowing admission of air to the space between the vapor heater and the outer housing, 65 below the level of the vapor inlet openings 72. The several cylindrical housing sections are inter-supported in any suitable manner as, for example, by means of spacing bolts 79 and 79a. The middle section 74 is preferably of frusto- 75

conical shape, as shown, so that the general shape of the housing may provide an annular space of upwardly decreasing cross-sectional area around the vapor heater, as above described, the 5 lower portion of said space or chamber being of relatively large cross-sectional area, as at A'' and the upper portion of said space comprising a throat B'' of relatively small cross-sectional area adjacent the upper level of air admission, at 10 opening 77. The stack portion of the combustion housing may comprise a frusto-conical member 81 provided with a shoulder 82 adapted to be supported upon the upper edge 75a of the upper section 75 of the outer housing. The stack is 15 shown in this case as provided with a hinged cover 83, hingedly secured at 84 to the upper end of member 81 and adapted to be swung away from over the stack, to some such position as shown in dot-and-dash lines at 85.

20 In the operation of the heater of the present invention, the liquid fuel in the heater base portion is heated by means of the vaporizing flame maintained beneath the air admitting means in the cover of the heater base portion, and the fuel is thus caused to produce combustible vapors which rise into the vapor heater and are superheated therein. The vapors pass from the vapor heater into the annular space between the vapor heater and the outer housing, and are contacted by atmospheric air and combustion caused to take place. When the apparatus is provided with air admitting openings of the type shown at 3b in Fig. 1, the air admitted through these 25 openings is mixed with the vapors passing into the vapor heater and is also heated therein. The admission of air in the above manner allows of very smooth and uniform operation of the heater as combustion of the heated vapors within the combustion housing is facilitated by said vapors 30 being relatively easily combustible due to the presence of the admixed and preheated air.

Referring to Fig. 1, for example, partial combustion is obtained in the annular space "A" from contact of the vapors with air admitted through 45 the openings 21, and the partially burned vapors, together with the products of partial combustion are caused to rise in the space A and are mixed with additional atmospheric air in the throat B, such additional air being admitted through the slots 22 and 23. The main combustion 50 of the vapors occurs in the space C above the vapor heater 41. The combustion in the annular space A and in the combustion space above the vapor heater 41 provides for maintaining the vapor heater at a temperature suitable 55 for heating of the vaporized fuel prior to contact thereof by atmospheric air. It will be seen that due to the relative configuration of the outer housing walls and the vapor heater walls, the vapors are caused to pass through the throat B at a considerable velocity, obtaining an optimum intermixing of the vapors and combustion air.

The device of the present invention thus 60 comprises means for heating the combustible vapors before intermixing the same with the combustion supporting air, and provides novel means for causing the combustible vapors to be mixed with combustion air and enter the main combustion zone at a high velocity, so that the combustion is obtained under optimum conditions.

It will be understood that any suitable form of stack may be provided for the device, said stack being of such length and shape as to provide for 65 the desired amount of draft, and also, prefer-

ably of sufficiently large cross-sectional area that the rate of passage of the gases therethrough allows of sufficient time for the substantially complete combustion thereof during such passage.

The heater of the present invention is adapted 5 to be lighted in the conventional manner, that is, by introduction of a burning lighting liquid into the interior of the combustion housing through the upper end thereof, and also into the fuel receptacle through the air admitting means such 10 as at 6'. The burning liquid introduced into the combustion housing serves to heat the walls thereof and the vapor heater, while the burning liquid introduced into the fuel receptacle serves to start the vaporizing flame beneath the air 15 admitting means and produce combustible vapors which pass through the vapor heater and are subsequently ignited and burned in the combustion housing.

I claim:

1. A combustion housing for an orchard heater comprising a vapor heater having an opening at its lower end to receive fuel vapor and having a side wall and a top wall closing the upper end thereof; an outer housing having a side wall 25 surrounding and spaced from said vapor heater side wall; and a stack portion extending upwardly from said outer housing above the level of said vapor heater; said outer housing side wall and said vapor heater side wall being so formed as to 30 define therebetween an annular chamber of upwardly decreasing cross-sectional area; said vapor heater side wall being provided at its lower portion with vapor outlet openings communicating with the lower portion of said annular chamber; said outer housing being provided with openings for admitting air to said annular chamber; and the interior of said stack portion communicating with the upper end of said annular chamber.

2. A combustion housing for an orchard heater as set forth in claim 1, said vapor heater side wall being of inverted frusto-conical shape and said outer housing side wall being substantially cylindrical in shape.

3. A combustion housing for an orchard heater as set forth in claim 1, said vapor heater side wall being substantially cylindrical in shape, and said outer housing side wall being of frusto-conical shape.

4. A combustion housing for an orchard heater comprising a vapor heater having an opening at its lower end to receive fuel vapor and having a side wall and a top wall closing the upper end thereof; an outer housing having a side wall surrounding and spaced from said vapor heater side wall to define therebetween an annular chamber; and a stack portion extending upwardly from said outer housing above the level of said vapor heater; said vapor heater side wall being 60 provided at its lower portion with vapor outlet openings communicating with said annular chamber; said combustion housing having openings for admitting air into the lower portion of said annular chamber adjacent the position of 65 said vapor outlet openings, and said outer housing side wall having openings at its upper portion for admitting air into said annular chamber adjacent the level of the upper end of said vapor heater; and the interior of said stack portion communicating with the upper end of said annular chamber, at least one of said first-mentioned and last-mentioned side walls converging 70 upwardly toward the other side wall in such manner that the cross-sectional area of said an- 75

nular chamber decreases upwardly to a minimum area adjacent the upper end of said vapor heater, and the air admitting openings at the upper portion of said outer housing side wall being located adjacent the level of said minimum cross-sectional area of said annular chamber.

5. A combustion housing for an orchard heater comprising a vapor heater having an opening at its lower end to receive fuel vapor and having 10 a side wall and a top wall closing the upper end thereof; an outer housing having a side wall surrounding and spaced from said vapor heater side wall to define therebetween an annular chamber; and a stack portion extending upwardly from 15 said outer housing above the level of said vapor heater; said vapor heater side wall being provided at its lower portion with vapor outlet openings communicating with said annular chamber; said combustion housing having openings for admitting 20 air into the lower portion of said annular chamber adjacent the position of said vapor outlet openings, and said outer housing side wall having openings at its upper portion for admitting air into said annular chamber adjacent the level of 25 the upper end of said vapor heater; and the interior of said stack portion communicating with the upper end of said annular chamber, said vapor heater side wall being of inverted frusto-conical shape and said outer housing side wall being substantially cylindrical in shape, whereby the cross-sectional area of said annular chamber decreases 30 upwardly to a minimum area adjacent the upper end of said vapor heater, and the air admitting openings at the upper portion of said outer housing side wall being located adjacent the level of 35 said minimum cross-sectional area of said annular chamber.

6. A combustion housing for an orchard heater comprising a vapor heater having an opening at 40 its lower end to receive fuel vapor and having a side wall and a top wall closing the upper end thereof; an outer housing having a side wall surrounding and spaced from said vapor heater side wall to define therebetween an annular chamber; and a stack portion extending upwardly from 45 said outer housing above the level of said vapor heater; said vapor heater side wall being provided at its lower portion with vapor outlet openings communicating with said annular chamber; said combustion housing having openings for admitting 50 air into the lower portion of said annular chamber adjacent the position of said vapor outlet openings, and said outer housing side wall having openings at its upper portion for admitting air into said annular chamber adjacent the level of 55 the upper end of said vapor heater; and the interior of said stack portion communicating with the upper end of said annular chamber, said vapor heater side wall being substantially cylindrical in 60 shape, and said outer housing side wall being of frusto-conical shape, whereby the cross-sectional area of said annular chamber decreases upwardly to a minimum area adjacent the upper end of said vapor heater, and the air admitting openings 65 at the upper portion of said outer housing side wall being located adjacent the level of said minimum cross-sectional area of said annular chamber.

7. A combustion housing for an orchard heater comprising a vapor heater having an opening at 70 its lower end to receive fuel vapor and having a side wall and a top wall closing the upper end thereof; an outer housing having a side wall surrounding and spaced from said vapor heater side

wall to define therebetween an annular chamber; and a stack portion extending upwardly from said outer housing above the level of said vapor heater; said vapor heater side wall being provided at its lower portion with vapor outlet openings communicating with said annular chamber; said combustion housing having openings for admitting air into the lower portion of said annular chamber adjacent the position of said vapor outlet openings, and said outer housing side wall having 10 openings at its upper portion for admitting air into said annular chamber adjacent the level of the upper end of said vapor heater; and the interior of said stack portion communicating with the upper end of said annular chamber, said air 15 admitting openings at the upper portion of said outer housing comprising at least two circumferential rows of vertically elongated, uniformly spaced slots, the respective rows being at different levels but overlapping one another and the slots 20 in the respective rows being arranged alternately in such manner that the upper ends of the slots in a lower row overlap and extend between the lower ends of the slots in a higher row.

8. A combustion housing for an orchard heater 25 comprising a vapor heater having an opening at its lower end to receive fuel vapor and having a side wall and a top wall closing the upper end thereof; an outer housing having a side wall surrounding and spaced from said vapor heater 30 side wall to define therebetween an annular chamber; a stack portion extending upwardly from said outer housing above the level of said vapor heater; said vapor heater being rotatably disposed with respect to said outer housing; and 35 scraper means secured to said vapor heater and rotatable therewith in scraping contact with the interior of said outer housing side wall; said vapor heater side wall being provided at its lower portion with vapor outlet openings communicating 40 with said annular chamber, and said outer housing being provided with openings for admitting air to said annular chamber.

9. A combustion housing for an orchard heater comprising a vapor heater having an opening at 45 its lower end to receive fuel vapor and having a side wall and a top wall closing the upper end thereof; an outer housing having a side wall surrounding and spaced from said vapor heater side wall to define therebetween an annular chamber; and a stack portion extending upwardly from 50 said outer housing above the level of said vapor heater; said outer housing side wall and said vapor heater side wall being so formed as to define therebetween an annular chamber of upwardly 55 decreasing cross-sectional area; said vapor heater side wall being provided at its lower portion with vapor outlet openings communicating with the lower portion of said annular chamber; said outer housing side wall being provided with air admitting 60 openings in the upper portion thereof adjacent the level of minimum cross-sectional area of said annular chamber; said stack portion being supported upon the upper edge of the outer housing side wall and in tight engagement therewith 65 and defining a main combustion chamber above said vapor heater communicating with the upper end of said annular chamber, and said stack portion having a depending collar extending downwardly around and spaced from said outer housing side wall to a level below said air admitting 70 openings in said last-named side wall.
